COVERED WAGON PLAYGROUND CLIMBER OR THE LIKE

Roland W. Johnson, Hastings, Nebr., assignor to American Play-World, Inc., Hastings, Nebr.

Filed July 27, 1970, Ser. No. 24,152

Term of patent 14 years

Int. Cl. D21—03

U.S. Cl. D34—5

Fig. 1

Fig. 3

FIG. 1 is a side elevational view of a covered wagon playground climber or the like showing my new design, the opposite side is a mirror image thereof.

FIG. 2 is a top plan view;

FIG. 3 is a front elevational view.

I claim:

The ornamental design for a covered wagon playground climber or the like, substantially as shown and described.
